UNITED STATES PATENT OFFICE.

HENRY G. SCHAEFER, OF LAKEWOOD, OHIO, ASSIGNOR TO THE GUSTAV SCHAEFER WAGON COMPANY, OF CLEVELAND, OHIO, A CORPORATION OF OHIO.

DOOR-OPERATING MECHANISM.

Application filed August 4, 1924. Serial No. 729,939.

The present improvements, relating as indicated to door operating mechanism, are designed more particularly for use in opening and closing a co-operating pair of doors such as are found in various types of passenger vehicles. It will be understood, however, that such improvements are equally adaptable for use in any location where the available room for swinging the doors is limited and where the operating mechanism requires to be simple and compact as well as sturdy.

To the accomplishment of the foregoing and related ends, the invention, then, consists of the means hereinafter fully described and particularly pointed out in the claim, the annexed drawings and the following description setting forth in detail certain mechanism embodying the invention, such disclosed means constituting, however, but one of various mechanical forms in which the principle of the invention may be used.

In said annexed drawings:

Fig. 1 is a side elevation of the front end of a motor bus showing the exterior appearance of a pair of doors arranged to be operated by my improved mechanism; Fig. 2 is a broken horizontal section taken on the plane indicated by the line 2—2, Fig. 1, and showing in plan a portion of the floor of the vehicle and certain parts of such operating mechanism; Fig. 3 is a vertical section taken on the plane indicated by the line 3—3, Fig. 2, and showing the doors in elevation with parts of the operating mechanism likewise occurring in elevation and parts in section; Fig. 4 is a plan view of the operating mechanism, similar to that appearing in Fig. 2, but on a somewhat larger scale and showing the parts in different positions; Fig. 5 is a top plan view of one of the doors, the associated parts of the operating mechanism likewise appearing in plan; Figs. 6 and 7 are horizontal sections of details taken on the planes indicated by the lines 6—6, and 7—7, respectively, Fig. 3; and Figs. 8, 9 and 10 are vertical sections of details taken on the planes indicated by the lines 8—8, 9—9 and 10—10, respectively, Fig. 3.

As indicated above, the particular vehicle in connection with which I have chosen to illustrate my improved door operating mechanism is a motor bus, such bus being of the

type wherein entrance to and exit from the body 1 is had by means of one or more steps 2 that lie wholly within such body and are depressed below the level of the floor 3. In any vehicle it is desirable, if possible, that the doors should not project beyond the side of the vehicle when open and I accordingly make the step 2 of such width that the two doors 4, 4, which are provided to close the door opening in the case in hand, may be accommodated transversely of such step when they are in their open position. In such position, in other words, one door will be aligned with one side of the step 2 and the other against the other side thereof. The manner in which such doors are mounted so as to permit of their movement from the closed position shown in Figs. 1 and 2 to such open position, and vice versa, can best be described in connection with the description of the operating mechanism proper.

Such operating mechanism includes as one main element a vertical shaft 5 that rises to a suitable height above the floor 3 adjacent the right-hand side of the driver's seat 6, such shaft being suitably journaled near its lower end in the floor and at its upper end in a rail or bracket 7. The upper end of said shaft is further provided with a handled operating lever 8 whereby it may be oscillated by the driver, the direction of movement of such lever for opening the door being towards the driver, i. e. in a counter-clockwise direction, as shown in Figs. 2 and 4. The lower end of shaft 5 projects downwardly through the floor to approximately the plane of step 2, or rather a trifle below such plane, and is provided with a lever arm 9 fixedly attached to such end and connected through a link 10 with a bar 11 that is pivotally attached at one end to the under side of the step adjacent one of the rear corners thereof.

Suitably journaled at its lower end in each forward corner of the step is a vertical shaft 12, preferably tubular in form for the sake of lightness, the upper end of such shaft being journaled in the corresponding upper corner of the door frame. The doors 4, 4, are hung from said shafts, respectively, by means of two arms 13 and 14 that project radially from each shaft, one above and the other below the door. Each door lies between the corresponding pair of arms 13 and

14 and is pivotally attached to the outer ends of said arms so as to be swingable about a vertical median line.

Extending transversely across the upper end of the doorway is an inverted channel member 15 and each door 4 is provided on its upper edge at a point lying beyond the point of attachment of arm 13 with a roller 16 that is guided in such channel. In order to complete the description of the door before returning to the operating means proper, it will be noted that as shown in Fig. 6, the outer vertical edge of each door is reinforced with an angle bar 17, the projecting side of which overlies the corresponding shaft 12 and is adapted to co-operate with a weather strip 18 of rubber or like material, attached to the adjacent portion of the door frame and thus make a tightly sealed joint. Similarly, the meeting vertical edges of the two doors, as shown in Fig. 7, are formed with complementary semi-circular grooves 19 in one of which is secured a piece of tubular weather stripping 20 that when the doors are closed effectively seals this joint. As shown in Figs. 8 and 9, a transverse plate 21 is secured to the front face of each door adjacent the upper edge thereof, such plate projecting far enough above the door to form a closure with the channel 15. A similar plate 22 is secured along the bottom edge of each door to form a closure in co-operation with the step 2.

Fixedly attached to the lower end of each shaft, such end projecting for the purpose a short distance beneath step 2, is a short lever arm 24 that is connected by means of a link 25 with approximately the mid-point of lever 11. The arrangement of parts is such that upon a swinging movement being imparted to said lever from the position shown in full lines in Fig. 4 to that shown in dotted outline, the arms 24, and thus shafts 12, will be oscillated through approximately an arc of 90 degrees. The radially projecting arms 13 and 14 that carry the corresponding doors 4 will of course be oscillated through an equal angle, the action being to swing the outer edge of each door inwardly along the adjacent side of the step as the front edge of the door is guided transversely across the door opening by reason of the engagement of roller 16 in channel 15 (see Fig. 5). When the opening movement is completed, each door will be held in substantially parallel relation with the sides of the step and will lie wholly within such step. When it is desired to close the door, the operating lever 8 is swung in a clockwise direction with the result that lever 11 is

drawn back to its initial position, as shown in full lines in Fig. 4, thereby oscillating the shafts 12 in a reverse direction to that just described. The operation, it will thus be seen, is simple yet positive and while ample clearance is provided for movement of the doors, nevertheless a tight closure is effected when they are brought together. As previously explained, it is not intended to imply any limitation in the use of my improved door operating mechanism or the operation of doors in a particular place such as a motor vehicle, but they may be obviously employed to equal advantage on street cars and in a variety of other fields.

Furthermore, a door operated as herein-before described may be hung horizontally instead of vertically, i. e. in a horizontally extending opening instead of a vertical one. Also the particular operating means for oscillating the shaft from which the door is hung may take on various forms, e. g. pneumatic or electric means may be employed instead of the manually operated means shown.

Other modes of applying the principle of my invention may be employed instead of the one explained, change being made as regards the mechanism herein disclosed, provided the means stated by the following claim or the equivalent of such stated means be employed.

I therefore particularly point out and distinctly claim as my invention:—

In mechanism of the character described, the combination of a co-operating pair of doors and a frame therefor; two vertical oscillatory shafts disposed alongside the respective outer edges of said door frame; two arms projecting radially from the opposite ends of each of said shafts, one above and the other below the adjacent door and respectively pivotally attached at their outer ends to the corresponding opposite edges of said door; a longitudinal guide fixed to the door frame parallel with the upper edges of said doors when aligned in closed position; a projection on each such upper door-edge beyond the point of attachment of the corresponding arm thereto, said projections movably engaging said guide; and means for simultaneously oscillating said shafts, said means including a lever arm on each shaft, a lever bar pivotally fulcrumed at one end and adapted to be swung about such axis, and links connecting said lever arms with said bar.

Signed by me, this 1st day of August, 1924.

HENRY G. SCHAEFER.
